CLAIM

The ornamental design for a care bed, as shown and described.

DESCRIPTION

FIG. 1 is a first perspective view of a care bed showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the care bed thereof;

FIG. 10 is an enlarged view of the selected portion 10 in FIG. 1; and,

FIG. 11 is an enlarged view of the selected portion 11 in FIG. 1.

The dashed lines in the drawings depict portions of the care bed that form no part of the claimed design. The dot-dash broken lines depict the bounds of the enlarged views that form no part of the claimed design.

1 Claim, 11 Drawing Sheets
